UNITED STATES PATENT OFFICE

148,520

DESIGN FOR A HOUSING FOR AIR CONDITIONING APPARATUS OR THE LIKE

George Irving Carter, Longmeadow, Mass., assignor to Harvey-Whipple, Incorporated, Springfield, Mass., a corporation of Massachusetts

Application July 17, 1946, Serial No. 131,661

Term of patent 14 years

(Cl. D62—4)

To all whom it may concern:

Be it known that I, George Irving Carter, a citizen of Dominion of Canada and subject of the King of Great Britain, residing at Longmeadow, in the county of Hampden and Commonwealth of Massachusetts, having invented a new, original, and ornamental Design for a Housing for Air Conditioning Apparatus or the like, of which the following is a specification, reference being had to the accompanying drawings, forming part thereof.

Fig. 1 is a plan view of a housing for air conditioning apparatus showing my new design;

Fig. 2 is a side elevational view of the housing shown in Fig. 1; and

Fig. 3 is an end elevational view of a housing for air conditioning apparatus shown in Figs. 1 and 2.

I claim:

The ornamental design for a housing for air conditioning apparatus or the like, as shown.

GEORGE IRVING CARTER.
